Jack C. Machos, 4503 Hoover St.,
Boise, Idaho 83705

Filed Nov. 8, 1966, Ser. No. 4,578

Term of patent 14 years

(Cl. D34—5)

FIG. 1 is a perspective view of a golf putter head showing my new design.

FIG. 2 is a top plan view of the golf putter head;

FIG. 3 is a side elevation of the golf putter head, the reverse side being a mirror image;

FIG. 4 is a bottom plan view of the golf putter head;

FIG. 5 is a left end view; and

FIG. 6 is a right end view.

The broken line showing of a golf shaft and handle in FIG. 1 is for illustrative purposes only.

I claim:

The ornamental design for a golf putter head, as shown and described.
